UNITED STATES PATENT OFFICE.

LEONARD S. LONGCOR AND WILLIAM M. DAWSON, OF BELVIDERE, ILL.

BUGGY-TOP SUPPORT.

SPECIFICATION forming part of Letters Patent No. 317,811, dated May 12, 1885.

Application filed August 28, 1884. (No model.)

To all whom it may concern:

Be it known that we, LEONARD S. LONGCOR and WILLIAM M. DAWSON, citizens of the United States, residing at Belvidere, in the 5 county of Boone and State of Illinois, have invented certain new and useful Improvements in Safety-Spring Attachments for Buggy-Tops, of which the following is a specification, reference being had therein to the accompanying 10 drawings.

Figure 1 is a side elevation of a buggy-top, erected, having our improvement applied to it. Fig. 2 is a rear view in detail of one side of the top and the improved attachment. Fig. 15 3 is a side view showing the buggy-top thrown back. Fig. 4 is a perspective view in detail of one form of spring-cushion applied to part of the seat-rail. Fig. 5 is a perspective view showing a spring, which is a modification of 20 the spring of Fig. 4. Fig. 6 is a central section of Fig. 5.

The object of our invention is to prevent the bows or rigid braces of buggy-tops from breaking or bending in consequence of suddenly 25 throwing back the top or in consequence of concussions on heavy roads; and the nature of our invention consists in the employment of spring-cushions applied on the fulcrum or pivot-bolts of the jointed side braces, as will 30 be hereinafter fully explained, when taken in connection with the annexed drawings.

Prior to our invention various spring devices have been essayed for the accomplishment 35 of the object we have in view, but such devices were unsightly and were liable to many practical objections by carriage manufacturers, jobbers, and individual purchasers. These objections we effectually obviate by our 40 improved device.

For the purpose of illustrating our invention and its application and advantages, we 45 shall refer to the annexed drawings, Figs. 1, 2, and 3 of which show well-known parts of a well-known buggy-top.

A designates part of the body of a buggy; B, the seat-rail with its arms; C, the back jointed brace, the lower end of which has its fulcrum on an offset, D, of the back rail, and is jointed thereto in the usual well-known 50 manner.

The main rigid brace E on each side of the buggy-top is jointed in front at its lower end at E'. This is the rigid or stiffening brace, which, with its fellow, aids materially in supporting the buggy-top, and this is the brace 55

which we have prevented from breaking or even bending. We do this in the following manner: The fulcrum extensions or offsets D are preferably square, in cross-section, and at their outer end male screw-threads are cut, 60 as shown in Fig. 5. On the top of each one of these fulcrum-offsets we apply a spring-cushion, F, and lock it in place by the same nut, a, which unites the braces thereto. This spring is provided with a vertical clip, b, 65 which is adjustable. It is also provided with a rectangular extension, b', which has a hole adapted to pass over either one of the offsets D.

Fig. 5 shows a modification of our invention, which consists in the adaptation of a 70 convolute spring, which may be capped or not. It may be desirable to cover or cap each spring with an inverted hood, the object being to guard against mud, and ice, &c., which might interfere with the proper action of the springs. 75

It will be observed that we employ a strong square extension of the seat-rail B, and that we do so construct the spring-cushion and apply it to said extension that the impact of the braces E will be directly over said extension, 80 and not in rear thereof. We are thus able to employ a very elastic spring, which is at the same time light, and we are also able to dispense with all auxiliary supports which are necessary where springs are extended back 85 of the supporting-rail.

Having described our invention, we claim—

1. The combination, with the square extension D of a buggy-seat rail, of a spring having an extension, b', lying longitudinally upon 90 said extension, as described, and terminating in an angular perforated portion fitted on the screw portion of said extension, the clip b, and the nut-fastening a, all constructed and adapted to operate substantially as and for the purposes described. 95

2. As a new and improved article of manufacture, the within-described safety attachment for buggy-tops, consisting of a spring having a base-extension, b', terminating at one 100 end in an angular perforated portion adapted to be secured to an offset of a seat-rail, substantially as specified.

In testimony whereof we affix our signatures in presence of two witnesses.

LEONARD S. LONGCOR.
WILLIAM M. DAWSON.
